C. I. LINDAU,
LIQUID FUEL BOILER FURNACE,
APPLICATION FILED MAR. 23, 1915.

1,152,897.

Patented Sept. 7, 1915.

Fig. 1.

UNITED STATES PATENT OFFICE.

CHARLES I. LINDAU, OF PEARCE, ARIZONA.

LIQUID-FUEL BOILER-FURNACE.

1,152,897.

Specification of Letters Patent. Patented Sept. 7, 1915.

Application filed March 23, 1915. Serial No. 16,407.

To all whom it may concern:

Be it known that I, CHARLES I. LINDAU, a citizen of the United States, residing at Pearce, in the county of Cochise and State 5 of Arizona, have invented certain new and useful Improvements in Liquid-Fuel Boiler-Furnaces, of which the following is a specification.

My invention relates to improvements in 10 boiler furnaces using liquid fuel, such as oil or the like.

An important object of the invention is to provide means of the above mentioned character, so constructed that the heat derived 15 from the combustion of the liquid fuel is transmitted in an economical manner to the receptacle or receptacles containing the water to be heated, without injury to the receptacle or receptacles.

20 A further object of the invention is to provide means of the above mentioned character adapted to effect the complete combustion, as far as possible, of the oil or liquid fuel used.

25 A further object of the invention is to provide means of the above mentioned character, embodying a surface having a large area upon which the flame is directed, the heat being reflected from the surface to the 30 boiler flues or tubes.

Other objects and advantages of the invention will be apparent during the course of the following description.

In the accompanying drawings forming a 35 part of this specification and in which like numerals are employed to designate like parts throughout the same, Figure 1 is a central vertical longitudinal sectional view through apparatus embodying my invention, and, Fig. 2 is a transverse vertical sectional view taken on line 2—2 of Fig. 1.

40 In the drawings wherein for the purpose of illustration is shown a preferred embodiment of my invention, the numeral 5 designates a heating shell or body portion of the furnace as a whole, which is formed of fire-proof material, such as fire brick or the like.

45 Arranged diagonally within the shell 5 are inclined tubes or flues 6, extending 50 downwardly toward the rearward end of the shell 5. These tubes or flues are spaced and their opposite ends communicate with end shells 7 and 8. The flues 6 are held stationary within the shell 5 by transverse bars or 55 members 9, as shown. Arranged upon the top of the shell 5 and inclosing the same is a

horizontal boiler shell 10, the interior of which is placed in communication with the end shell 8 by a coupling 11. The opposite end of the boiler 10 has communication with 60 a pipe 12 in turn communicating with the end shell 7, as shown.

The numeral 13 designates an arch, extending across the flues 6, near their rearward ends, but spaced a substantial distance 65 from the rearward end of the shell 5, and the outlet opening 14 thereof. The water is preferably fed into the bottom of the shell 7 or drum 10.

The numeral 15 designates a blow-off 70 pipe, communicating with the shell 7, as shown.

The numeral 16 designates the combustion chamber of the shell 5 arranged in the forward portion thereof below the flues 75 6, as shown. This combustion chamber has a bottom wall 17, which is longitudinally inclined and extends upwardly toward its rearward end. The wall 17 is transversely corrugated for providing the maximum 80 heating surface and the corrugation is preferably effected by means of inclined bricks or members 19, arranged in a stepped order, providing heating surfaces 20, which are inclined and extend upwardly toward the 85 rear end of the shell 5. These members or bricks 19 are preferably fire bricks while the same may be of any suitable heat resisting material. The fire bricks are laid upon a filling 20'. At the rearward end of 90 the inclined bottom wall or floor 17 is a deflector wall 21, formed of heat resisting material, and having a forwardly extending inclined face 22, as shown.

In the forward end wall 22 of the shell 95 5 is an opening 23 receiving a pipe 24, having connection with an oil or liquid fuel burner 25, disposed above and near the inclined bottom wall 17, as shown. This burner is preferably of the type shown 100 in my allowed application for burners, Serial No. 877,151, filed December 14, 1914, Patent No. 1,131,718. The burner 25 is adapted to atomize or vaporize the oil or liquid fuel and mix the same with air or steam. The fuel passes through a tip 26 and the flame and products of combustion are discharged in a downward direction, to engage with the bottom wall 17, as shown. Arranged below and adjacent the burner 105 25, are openings 27, formed in the end wall 22, having their forward ends in connec- 110

tion with an air space 28, adapted to be covered and uncovered by a door or damper 27', as shown. At their rearward ends the openings 27 discharge air in a substantially horizontal direction against the inclined corrugated surface of the bottom wall 17, to become thoroughly mixed with the gases and products of combustion from the burner. This air, gases and products 10 of combustion, by engaging with the inclined corrugated surface of the bottom wall 17, form vortices, whereby the gases are intimately mixed and the combustion of the fuel is completed to a high degree. 15 The corrugated surface of the bottom wall 17 is large, and the heat reflected or radiated therefrom passes upwardly and longitudinally toward the face 22, and is deflected thereby forwardly, to pass between 20 the flues 6. Above these flues the heat and products of combustion travel rearwardly longitudinally of the flues and then downwardly between the members 9. The heat and products of combustion then travel upwardly and rearwardly between the flues and discharge through the opening 14 to the atmosphere, stack or the like. Instead of employing a single burner 25, two or 25 more may be employed, in which event the openings 27 are separated by partitions arranged corresponding to the number of burners, and a door or damper employed to cover and uncover the opening or openings between each pair of partitions.

30 35 It is to be understood that the form of

my invention herewith shown and described is to be taken as a preferred example of the same, and that various changes in the shape, size, and arrangement of parts may be resorted to without departing from the 40 spirit of the invention or the scope of the subjoined claim.

Having thus described the invention, what I claim is:

The combination with a fire box of a 45 furnace, comprising an inclined bottom wall increasing in height inwardly and having inclined transverse steps, and a vertical transverse wall arranged at the inner high end of the bottom wall and projecting upwardly therebeyond for a substantial distance and having a forwardly inclined face upon its forward side; of a burner arranged substantially horizontally within the fire box over the outer lower end of the bottom 50 wall and having a downwardly discharging flame outlet device arranged at substantially a right angle to its body portion, and means spaced a substantial distance from the burner for introducing air into 55 the fire box above the lower end of the bottom wall and the burner.

In testimony whereof I affix my signature in presence of two witnesses.

CHARLES I. LINDAU.

Witnesses:

GEORGE W. FLEETHAM,
CHAS. S. MONMONIER.
